(57) **CLAIM**

The ornamental design for a truncated top bowling pin shaped vacuum container, as shown and described.

DESCRIPTION

FIG. 1 is an isometric view of a vacuum container showing my new design;

FIG. 2 is top view thereof;

FIG. 3 is a front elevation view thereof, with the rear elevation view a mirror image thereof;

FIG. 4 is a bottom view thereof; and,

FIG. 5 is a right side view thereof; with the left side elevation view a mirror view thereof.
